MOSES A. JOHNSON, OF LOWELL, MASSACHUSETTS.

Letters Patent No. 73,727, dated January 28, 1868.

IMPROVEMENT IN FELTED FABRICS.

The Schedule referred to in these Letters Patent and making part of the same.

TO ALL WHOM IT MAY CONCERN:

Be it known that I, MOSES A. JOHNSON, of Lowell, in the county of Middlesex, and State of Massachusetts, have invented certain new and useful Improvements in Felt-Wool Cloth, made from "side-drawings," so called; and I do hereby declare the following to be a full, clear, and exact description of the same, reference being had to the accompanying drawings, making a part of this specification, in which—

Figure 1 represents a series of the "side-drawings," or rovings, laid side by side, preparatory to felting.

Figure 2 represents a section, taken across a series of "side-drawings," or rovings, as they appear after being rolled or slightly felted.

Figure 3 represents a specimen of the felt-cloth, as it appears when finished.

Figure 4 represents the appearance of a specimen of cloth made by laying the "side-drawings" or rovings across each other in two directions.

In figs. 1, 2, and 3, I have shown the "side-drawings" or rovings, as of different colors, which colors appear in order in the finished cloth. That shown in fig. 4 is made of "side-drawings," or rovings, of uniform color.

Ordinarily, felt-cloth is produced by forming a bat from the cards directly upon long endless aprons, layer after layer, to get the required thickness. To overcome certain objections to felt-cloth, made as above stated, there have been various devices essayed to place the fibres of wool as they leave the card at angles to each other. Felted cloth, as ordinarily formed, is more spongy and elastic in one direction than in the other, and, when once stretched in the weakest direction, will not readily come back into place again.

"Side-drawings" are the product of an ordinary wool-card, taken off in a strand or roving continuously at the side of the card, and wound upon bobbins. They are the product of the "breaker" cards, each set of woollen cards being composed of three distinct kinds, called "first and second breaker," and "finisher." The product of a "finisher" is ordinarily a series of smaller ropings or rovings. The product of the "breaker" cards is put into one large "side-drawing," and a number of these are fed into the "finisher," and placed usually upon a frame or creel.

My invention consists in the manufacture of a felt-cloth, so called, by forming the bat of a series of side-drawings or rovings, laid crosswise by any suitable mechanism, or merely run in lengthwise, from spools or creels, or otherwise.

The advantages gained by my mode of manufacture are many, and among them are, more uniform elasticity of the cloth, (the fibres of wool being more interlaced at different angles;) capacity to form any width of goods, independent of the width of the card; great economy of space, by dispensing with the use of the long, continuous aprons, and feeding direct to the felting-machine; also, the combining of various colors.

In fig. 1, *a a a* represent a series of "side-drawings" or rovings, laid side by side. These "side-drawings" or rovings pass from the card through a revolving trumpet at the side of the card, and thence between rollers sufficiently weighted to draw the roving through the trumpet. They are then wound upon spools into balls, and in this condition also pressed. The result is a ribbon, instead of a cylindrical thread, as it leaves the trumpet. A series of these ribbons is put or laid in juxtaposition, to form the felt, and is subjected, in felting, to a compression or compresure of the platea or felting-plate. This compression causes the rovings to overlap as ribbons would, and as seen at *b b b*, &c., in fig. 2. In ordinary manipulation, these "side-drawings" or rovings would not need to be so compressed at the card, but would, if received into jams or boxes, be more cylindrical. Even then, however, there would be an interlapping, but not so marked in one direction, but producing more uniformity, and a more desirable result. It is this overlapping, in its soft, spongy condition, which gives the evenness or uniformity to the bat. Otherwise it would be ridgy, or full of ridges and depressions.

When the felted cloth is composed of "side-drawings" or rovings of different colors, it will, when finished, show the overlappings, as seen at *c c c*, fig. 3. If the felted cloth be composed of "side-drawings" or rovings of a single color, whether laid lengthwise, or lengthwise and crosswise, the overlappings will not show, though they exist. In fig. 4, a piece of cloth is represented, as made with the ribbons laid both lengthwise and crosswise, and of rovings of a uniform shade or color, and in this no marks or lines are seen other than those given to it by the felting-machine.

For light cloths a series of rovings might be used, as they are delivered from the "finisher," but I prefer

to take the "side-drawings" from the "breaker-cards." The same process may be used in the manufacture of hat-bodies, Balmoral skirts, or other irregularly-shaped apparel made over a former. And to form these the "side-drawings" or rovings would need to be folded in layers over the cone, or former, or mould, to make the bat, or wound around the cone or former in the form of a helix, with abutting or overlapping edges.

Having thus fully described my invention, what I claim therein as new, and desire to secure by Letters Patent, is—

The manufacture of felt-cloth, by forming the bat, and as it is fed to the felter, of a series of side-drawings or rovings, laid together lengthwise or crosswise, or lengthwise and crosswise both, and run in from spools, creels, or otherwise, substantially as herein described and represented.

MOSES A. JOHNSON.
